(57) **CLAIM**

I claim the ornamental design for a dispenser, as shown and described.

DESCRIPTION

FIG. 1 is a top plan view of a dispenser showing my new design;

FIG. 2 is a side elevational view thereof;

FIG. 3 is a bottom plan view of FIG. 1, with the slide-able tab in a closed position; and,

FIG. 4 is a bottom plan view of FIG. 1, with the slide-able tab in an open position.
